AUTOMATIC BAG SEWING MACHINE

Frank Lombardo, Kansas City, Mo.

Application August 11, 1944, Serial No. 548,976

8 Claims. (Cl. 112—10)

1

This invention relates to equipment employed in the manufacture of bags, in the nature of those required to be stitched along at least two marginal edges, and the primary aim is to provide sewing apparatus having unique and novel conveying elements in association with a plurality of sewing machines, whereby the bags may be transported one at a time into operative relation with each machine.

This invention has for an important object, the provision of bag making equipment wherein is included, in combination with at least two sewing machines, a conveyor for moving the bags past the several machines to successively stitch the marginal edges of the bag blank, said conveyor being constructed to shift the bags after leaving one machine and before introducing the same to the next succeeding sewing machine.

Another object of this invention is the provision of a bag making machine having parts for automatically presenting each of several marginal edges to separate sewing machines, as the bag is moved along a rectilinear path of travel.

This invention has for further aims the provision in a bag making machine, of parts for severing the threads after each marginal edge of the bag has been stitched; means for automatically moving the thread severing parts to and from the operative position; elements for supporting the bags for movement through the machine and for automatically ejecting the bags after the same have been stitched along at least two edges thereof; and unique manually operable clamps for holding the bags against rotatable tables with marginal edges disposed to be engaged by the sewing machines forming a part of the equipment.

Other objects of the invention will appear during the course of the following specification, referring to the accompanying drawings, wherein:

Fig. 1 is a top plan view of an automatic bag sewing machine made in accordance with the present invention.

Fig. 2 is a side elevational view thereof.

Fig. 3 is a vertical transverse, enlarged sectional view through a portion of the machine, taken on line III—III of Fig. 2.

Fig. 4 is a fragmentary detailed sectional view taken on line IV—IV of Fig. 3.

Fig. 5 is a fragmentary sectional view taken on line V—V of Fig. 1.

Fig. 6 is an enlarged detailed sectional view taken on line VI—VI of Fig. 2; and

Fig. 7 is an inverted plan view of one of the rotatable table assemblies, entirely removed from

2

the operative relation with the remaining portion of the machine.

The preferred embodiment of the invention which has been chosen for illustration, is capable of sewing two marginal edges of a bag as the same is passed through the equipment and a single operator is all that is required to manipulate the apparatus, it being but necessary to place the bags upon continuously moving tables as they pass the feeding station. When the folded blanks of the bags are introduced to the machine, they are stitched along two marginal edges, the threads are automatically severed after each stitching, and the completed bag is ejected from the machine as the tables are cleared for the further introduction of additional, unstitched bag blanks.

The machine comprises a suitable frame-work 10 upon which is mounted all of the operating parts, and particularly the endless chains 12, disposed in spaced apart relation and carried by sprockets 14 adjacent to each end of frame 10. Sprockets 14 are secured to shafts 16 journaled in slidable bearings 18 that are in turn held in desired adjusted condition by set screws 20.

A series of plates 22 attached to chains 12 by integral ears 24 maintain tables 26 in place. Each plate 22 carries a turn-table 26 through the medium of stub shaft 28, roller bearing 30, and stop collar 32. When a table 26 is so mounted upon plate 22, it is free to rotate about the axis of stub shaft 28, limited only by pin 34 which extends through an arcuate slot 36 provided in plate 22.

A spring 38 yieldably maintains table 26 in the position with its longitudinal axis in alignment with the path of travel of chains 12 and the series of tables 26. This spring 38 has one end anchored as at 40 to the underside of plate 22 and its opposite end fastened as at 42 to stop collar 32, pinned to stub shaft 28.

Ears 24 are pivotally attached to chain 12 by passing a bolt or analogous means 44 through the perforations of ears 24 and thence through the openings in the overlapped ends of the links of chains 12.

Each table 26 has a specially devised clamp for holding the bag 46 thereon with two of its marginal edges projecting beyond the edges of the table. The dot-and-dash outline of bags 46, shown in Fig. 1, clearly reveals the manner in which the clamp now about to be described, operably maintains the bag in place upon table 26 for movement through the two sewing machines.

The bag clamp comprises bearings 48 and 50, integral with table 26 and journaling shaft 52 upon which is mounted a drum 54 having a cam slot 56. An arm 58 secured to shaft 52 carries beam 60 at its free end, which beam extends in parallelism with one edge of table 26. Another arm 62 joined to shaft 52 connects with beam 60 at its free end to complete a three-sided upper frame portion below which a bag contacting frame is hung through the medium of short coil springs 64. The lower frame is two-sided because it is necessary only to exert pressure upon bag 46 along the marginal edges to be stitched.

Bar 68 hung beneath beam 60 is free to move toward and from beam 60 because of springs 64, and further because a yoke 70 serves as a guide. A similar yoke 72 depending from arm 62 straddles bar 74 hung beneath arm 62. A leaf spring 76 anchored as at 78 to exert downward pressure on arm 62 of the upper frame cooperates with spring 80 to establish a compensating yet sufficient pressure upon the bag when it is resting upon table 26 and beneath bars 68 and 74.

Spring 80 has one end attached as at 82 to table 26 while its opposite end is fastened as at 84 to the end of shaft 52 and to one side of the longitudinal axis thereof. The disposition of spring 80 is illustrated in Fig. 3 and must be such as to pass the center of shaft 52 when the entire clamp assembly is lifted to the position shown in dotted lines of Fig. 3. When in such place, the spring will hold the clamp in the elevated condition, ready for the operator to place a bag 46 and lower the clamp thereagainst. When the clamp is lowered, spring 80 will assume that position shown in full lines of Fig. 3, and thereby yieldably hold the clamp and its underlying bag against the top of table 26.

There is a clamp of the aforementioned type secured to each of tables 26 and when the drums 54 are carried past pin 86 mounted on frame 10, the engagement of this pin by cam slot 56 will move the clamp to the dotted line position shown in Fig. 3 to eject, by gravity, the bags that have been stitched.

Pin 34 projects through slot 36 in plate 22 for engagement with guide member 88, mounted on frame 10 and disposed in the path of travel of the several pins 34, as illustrated in Fig. 1. When the tables 26 and all the parts associated therewith, are moved toward member 88 by chains 12, pins 34 of each table assembly will strike the edge of member 88 and cause table 26 to rotate about stub shaft 28 through a 90° arc and assume the position shown to the left in Fig. 1.

The movement of table 26 is against the tension of spring 38 and as soon as guide member 88 releases pin 34, spring 38 will draw table 26 to the normal position or where its longitudinal axis is in alignment with the path of travel as shown to the right in Fig. 1. A portion of table 26 and its related parts is shown in Fig. 1, after member 88 has released its engagement and the pin 86 is within cam slot 56, as seen in Fig. 2.

The bags 46 are laid upon each table 26 as they pass the operator's station, which is at the right end of the machine, as viewed in Fig. 2. The clamp assembly is dropped upon the bags to hold the marginal edges 90 and 92 beyond the proximal edges of table 26.

Two sewing machines of like character are disposed in tandem and in the path of travel of bags 46. These sewing machines are generally designated by the numeral 94 and each is equipped with the conventional presser foot 96 and needle 75

98. The machines are mounted upon a portion of frame 10 and the tables 100 thereof are in substantially the same horizontal plane as the upper face of tables 26, to the end that marginal edges 90 and 92 are drawn beneath presser foot 96 for stitching.

After the first machine 94 has stitched marginal edge 90 of bag 46, threads will trail behind bag 46 and join machine 94 to the bag until the threads are severed. Automatic means for cutting these threads is provided for each machine 94 and the description of one will serve to clarify the construction and operation of all.

The chain 12 next to machines 94 carries a number of cams 102 arranged to strike plunger 104 reciprocably mounted on frame 10 and held in normal position by spring 106. A cutter wheel 108 rotatably mounted on the end of arm 110 is driven through the medium of belts 112 extending to the power mechanism of machine 94. Cutter wheel 108, therefore, constantly rotates at a relatively high rate of speed whether arm 110 is in the position shown in Fig. 3, or whether it is swung to a thread severing position when plunger 104 is engaged by one of cams 102. After bag 46 is moved past the plane in which cutter wheel 108 is disposed, plunger 104 is kicked outwardly in the direction of the arrow in Fig. 3, to swing arm 110 toward the trailing threads between bag 46 and needle 98.

Plunger 104 is joined to bell crank lever 114 coupled to another bell crank lever 116 by link 118. Link 120 interconnects bell crank lever 116 with the upper end of arm 110 mounted to rotate about the axis of pintle 122. Part of frame 10 supports arm 110 and the swinging movement of arm 110 serves to sever the threads before pin 34 on the table carrying the bag being treated, strikes guide member 88 to dispose marginal edge 92 in place to be stitched by the next succeeding machine 94. There is a cutting mechanism for each machine and cams 102 will insure operation at the proper moment.

The preferred form of the automatic bag sewing machine has been clearly disclosed and the function and manner of operation has been made clear during the course of the foregoing specification. It is obvious that all the attendant need do is to place the bag 46 on each table as it passes his station, lower the clamp to hold the bag in place on each table 26, and perform this task as each table presents itself. Not only will the two marginal edges 90 and 92 be stitched, but the threads will be severed at the proper time, and the completed bag will be ejected when the clamp is moved to a point where the bag may drop by gravity from each table 26 at the end of the machine.

Obviously, bag sewing equipment having specific structural details differing from those shown and explained may be made without departing from the spirit of the invention or scope of the appended claims.

Having thus described the invention, what is claimed as new and desired to be secured by Letters Patent is:

1. In bag making equipment of the character described, a pair of sewing machines mounted in tandem; a conveyor for moving the bags along a straight path of travel past both sewing machines; a bag supporting table pivotally carried by said conveyor; and mechanism for turning the table and the bag held thereby after leaving one machine and before it reaches the second machine.

2. In bag making equipment of the character described, a pair of sewing machines mounted in tandem; a conveyor for moving the bags along a path of travel past the sewing machines; means for severing the thread applied by each sewing machine after the bags have been stitched along certain marginal edges by the machines; and a bag supporting table rotatably carried by said conveyor for turning the bag held thereby after one marginal edge thereof has been stitched by one machine and after the thread therefrom has been severed and before the bag reaches the second machine to a position for stitching another marginal edge of the bag by said second machine.

3. In bag making equipment of the character described, a pair of sewing machines mounted in tandem; a conveyor for moving the bags along a straight path of travel past the sewing machines; clamps shiftably mounted on the conveyor to hold the bags in positions engageable by the sewing machines; and means for releasing the bags from the clamps after both sewing machines have acted thereon.

4. In bag making equipment of the character described, a pair of sewing machines mounted in tandem; a conveyor for moving the bags one-at-a-time along a straight path of travel past the sewing machines where a marginal edge is to be stitched by each machine respectively; clamps shiftably mounted on the conveyor to hold the bags in positions engageable by the sewing machines; means for releasing the bags from the clamps after the sewing machines have acted thereon; and means operable by the conveyor for severing the thread from the sewing machines after the bags have passed therethrough and before the bags are ejected from the equipment.

5. In bag making equipment of the character described, a plurality of sewing machines; a conveyor for moving the bags along a straight path of travel past the sewing machines one-at-a-time; clamps rotatably mounted on a vertical axis on the conveyor for holding a marginal edge of each

bag in operative relation to one of the sewing machines whereby the edges of the bags are individually stitched; and means for shifting the clamps to an inoperative position to eject the bags from the equipment after all the sewing machines have acted thereon.

5 6. Bag making equipment of the character set forth in claim 5, wherein the clamps each have yieldable means for holding them in an inoperative position, said means serving as the clamping force when the clamps are holding bags therein.

10 7. In bag making equipment of the character described; a plurality of sewing machines; a conveyor for moving the bags along a path of travel past the sewing machines one-at-a-time; means for rotating the bags after they have been stitched by one sewing machine and before the next succeeding sewing machine stitches the bag; and means for severing the thread joining the bag and one machine before the bag is rotated to enter the next machine.

15 8. In bag making equipment of the character described, a plurality of sewing machines; a conveyor for moving the bags along a path of travel past the sewing machines one-at-a-time; a clamp for securing the bags in place on the conveyor; and means for rotating the clamp and the bag held thereby through a 90° turn after one marginal edge of the bag has been stitched by one of 20 the sewing machines and before the conveyor has moved the bag into operative position with the next succeeding sewing machine.

30 FRANK LOMBARDO.
